United States Patent

Des. 237,249
Patented Oct. 21, 1975

237,249

THUMB KNIFE

Lester J. Gendron, P.O. Box 1177,
Madera, Calif. 93637

Filed Jan. 17, 1974, Ser. No. 435,012

Term of patent 14 years

Int. Cl. D8—03

U.S. Cl. D8—98

Fig.-1

Fig.-2

Fig.-3

Fig.-4

Fig.-5

FIG. 1 is a top plan view of a thumb knife, showing my new design;

FIG. 2 is a side elevational view, the opposite side being in mirror symmetry;

FIG. 3 is a bottom plan view;

FIG. 4 is a rear elevation view; and

FIG. 5 is a front elevational view.

I claim:

The ornamental design for a thumb knife, as shown and described.
